15 Claims. (Cl. 219—46)

1

This invention relates to an electric temperature control system and is designed more particularly for use with an electrically heated blanket, or the like.

One object of the invention is to provide such a control system which is highly efficient in operation, simple in construction and relatively inexpensive to produce and operate.

A further object of the invention is to provide such a control system in which the heating element is maintained at all times, when the system is in operation, at a temperature closely approaching the temperature for which it is set.

A further object of the invention is to provide such a control system which is responsive to ambient, or room, temperatures.

A further object of the invention is to provide such a control system with an amplifier which positively and accurately controls a relay in the heater circuit.

A further object of the invention is to provide such a control system which is entirely safe in operation and in which no adverse effect can result from the accidental breaking, or otherwise opening, of the heater circuit.

Other objects of the invention may appear as the system is described in detail.

In the accompanying drawings, Fig. 1 is a circuit diagram of the system; and Fig. 2 is a dia-grammatic illustration of the amplifier.

In these drawings I have illustrated one embodiment of my invention and have shown the same with a preferred form of circuit and with a preferred type of amplifier, but it is to be understood that the circuit and the amplifier may take various forms, and that the control system may be used for various purposes, without departing from the spirit of the invention.

In the form here shown the main circuit comprises conductors 5 and 6 connected respectively with terminals A and B, whereby the system may be connected with an alternating current power line, as by plugging the same into an ordinary electric outlet. This main circuit includes a bridge circuit one leg of which constitutes a resistance heater Rh, which may be of any character suitable for its intended use but which, when adapted for insertion in a blanket, is usually of substantial length and is distributed through a large portion of the blanket. The heater Rh is connected by conductor 7 and resistor R1 with conductor 6, and through that conductor is connected with resistors Rc and Ra. The resistor Rc is connected through a conductor 8 and resistor R2 with a conductor 9, which in turn is

connected with the conductor 10, which is connected with that end of the resistor Rh opposite the end with which the conductor 7 is connected. The conductor 8 is also connected with an amplifier X and the conductor 1 and resistor R1 are also connected with the amplifier by a conductor 11. The resistor R1 being between the heater and the terminal B should be of relatively small value and the opposed resistor R2 should be of a correspondingly large value. The resistors Rc and Ra constitute that leg of the bridge which is opposed to and balances the heater Rh. The resistor Rc is a variable resistor which can be manually adjusted to determine the temperature at which the heater Rh is to be maintained. The resistor Ra is responsive to ambient, or room, temperature, and is, therefore, preferably wound of wire having a high positive temperature coefficient, such as iron, nickel, or copper. The two resistors, Rc and Ra, are preferably mounted in a control box 12 spaced from the heater and the other elements of the system so that they will receive no heat from such elements but the resistor Ra will respond to changes in the ambient temperature and thereby vary the resistance of the heater Rh in accordance with the variations in the room temperature. The heater circuit is connected with the terminal B through a relay, one switch member 13 of which is connected with the conductor 9 and the other switch member 14 of which is connected with the conductor 5. The relay winding is shown at 15.

The relay is controlled by the amplifier X which is preferably of such a character that the relay will operate to maintain the temperature of the heater Rh substantially constant while the system is in operation. This is preferably accomplished by so controlling the operation of the relay that the heater circuit will be closed at frequent intervals regardless of the temperature of the heater. For this purpose I employ two or more vacuum tubes, the plate circuit of one of which includes the relay winding, and the grid bias of that tube being controlled by means connected in the plate circuit of a second tube, the output of which is responsive to variations in the resistance of the heater Rh. In the illustrated amplifier I have provided three tubes designated respectively as V1, V2, and V3. The cathode 16 of tube V3 is connected by a conductor 17 with a terminal A, and the plate 18 of tube V3 is connected with terminal B through conductors 19 and 6, the winding 15 of the relay being included in the plate circuit. The cathode 20 of tube V2 is connected with terminals A and B through a re-

sistance divider comprising a part R3 connected with the conductor 17 and a part R4 connected with the conductor 6. The plate 21 of tube V2 is connected with the terminal A through the conductor 22, a resistor R6 and the conductor 17. A condenser C1 is connected between the conductors 22 and 17 in parallel with resistor R6, and the condenser C1 and the conductor 22 of the plate circuit are connected with the grid 23 of the tube V3. The cathode 24 of tube V1 is connected through a conductor 25, and resistor R2 with the terminal B. The plate 26 of tube V1 is connected by a conductor 27 with the grid 28 of tube V2 and is also connected through a resistor R5 and conductor 17 with the terminal A. The grid 29 of tube V1 is connected with the heater Rh and resistor R1 of the bridge circuit through a resistor 30, the resistor 30 being added to prevent grid current flow during opposite cycles of the line voltage. The cathodes of the tubes may be heated in any suitable manner and in the present instance each tube is provided with a separate heater 31, which is connected in the main circuit as by conductors 32 and 33 as shown in Fig. 1. The tubes V1 and V2 being connected in cascade and the cathode of tube V2 being connected with the resistance divider R3, R4 across the line and both tube plate circuits being connected with terminal A of the alternating current line, the tubes V1 and V2 will draw current only when terminal A is positive, and the plate circuit of the tube V3 being connected with the terminal B will draw current only when terminal B is positive. The two parts of the resistance divider R3 and R4 are of approximately the same value, and during the brief interval, or one-half cycle, that terminal A is positive the cathode of tube V2 will be positive with respect to the cathode of tube V1 by approximately one-half the line voltage, and since resistors R1 and Rc plus Ra are small in value in comparison with the heater Rh and resistor R2 the cathode of tube V1 has substantially the potential of terminal B. Therefore, assuming that the line has a voltage of 120 volts, and that the resistance of R1 is 5 ohms and the resistance of the heater Rh is 75 ohms, the grid of tube V1 will be $7\frac{1}{2}$ volts positive and the cathode of tube V2 will be 60 volts positive, when the relay is closed.

When the relay is open both the cathode and the grid of tube V1 will be zero with respect to terminal B, and the grid of the tube V1 will have no negative bias and tube V1 will be fully conducting. Thus there will be a large voltage drop across resistance R5, and the plate of tube V1 and the grid of tube V2 will be negative with respect to the cathode of tube V2. Tube V2 will then be non-conducting and no current will flow through resistance R6 to the plate of tube V2 and the condenser C1 will discharge through resistance R6. When the relay is closed and the grid of tube V1 has a positive voltage of say 7 compared with terminal B, and assuming that the values of resistors Rc and R2 are so proportioned that the cathode of tube V1 has a positive voltage of 8 volts, the grid of tube V1 will have a negative voltage of 1 volt. Under such conditions the voltage drop through resistor R5 will decrease because tube V1 is drawing less current, the grid of tube V2 will become less negative with respect to its cathode and tube V2 will draw current. This current flows through resistor R6 and causes condenser C1 to be charged negatively with respect to terminal A.

As has been above explained, condenser C1 is

connected with the grid 23 of tube V3, and the condenser being of large capacity as compared with the resistor R6 will remain charged during the interval that the alternating current voltage is changing its polarity. Thus, when terminal B is positive, tube V3 will draw current from the line and that current will decrease as the charge across condenser C1 increases. As the resistance in the heater Rh increases and its temperature rises, the output current of tube V3 will decrease until it is insufficient to retain the relay closed. After the relay has opened, there will be no current flow through the plate circuit of tube V2 and condenser C1 will discharge across resistor R6, and when the charge has been reduced to a predetermined value plate 18 of tube V3 will again draw current in sufficient quantity to close the relay, which will then remain closed until the temperature of the heater reaches the value for which it is set.

In the present apparatus the values are such that the tube V3 will draw current sufficient to close the relay when the voltage across condenser C1 and resistor R6 is 10 volts or less, and the relay will remain closed until the voltage increases to 20 volts or more. It may be assumed that the voltage across condenser C1 and resistor R6 is 20 when the grid of tube V1 has a negative bias of 1 volt and that the voltage across the condenser C1 and resistor R6 is changed by an amount equal to one thousand times the change in the grid voltage of tube V1. Under such conditions each 1.0 ohm change in the value of resistance of heater Rh will cause a change of current of $\frac{1}{80}$ through heater Rh and resistor R1 which will in turn cause a change of $7\frac{1}{2}/80$ or .094 volt in the grid voltage of tube V1. Thus each .1 ohm variation in the resistance of heater Rh causes a change of about 9.4 volts across condenser C1 and resistor R6. If heater Rh has a positive resistance-temperature coefficient of .00133 ohm per degree Fahrenheit, this .1 ohm change in a 75 ohm heater corresponds to about 1° F. change in temperature.

The capacity of the condenser C1 as compared to resistor R6 will, of course, be determined according to the required operation, and in the present instance the proportions are such that about twenty seconds are required for the voltage across the condenser and resistor to decrease from 20 volts to 10 volts. The resistance of heater Rh being 75 ohms at the desired temperature, the relay will open with 20 volts across the condenser and resistor when the resistance of heater Rh reaches that value. The relay will then remain open for the twenty seconds required for the voltage across the condenser and resistor to drop to 10 volts, since there is no grid bias on tube V1 and no current will be drawn by the plate of tube V2. During this twenty seconds the heater will have cooled off slightly so that when the relay again closes it will stay closed until the heater has again reached the temperature for which it has been set. The length of time required to do this will be dependent upon the amount that the heater Rh has cooled during the twenty second interval. If the heater Rh has not cooled appreciably during the twenty second interval, the relay will remain closed only long enough for the condenser C1 to charge from 10 volts to 20 volts through the plate circuit of tube V2. If the resistance of R6 is 500,000 ohms and the plate resistance of tube V2 is 40,000 ohms then the charging of the condenser will require only 1.6 seconds. Thus the minimum current the controller is able

to put into the control circuit is about 8% of the maximum value. In a 150 watt blanket this is about 12 watts on the average, which is scarcely perceptible to the sleeper, whose heat radiation amounts to about 60 watts.

In practice the value of resistor R_2 is about one thousand times that of the heater R_h , that is, approximately 75,000 ohms, and resistor R_c plus resistor R_a is likewise one thousand times that of resistor R_h , or about 5,000 ohms. Therefore, if the heater R_h changes 1 ohm for each 1° of temperature change resistor R_c will be changed 6.6 ohms to effect a change of control temperature of 1° F. If resistor R_a is wound with iron wire having a temperature coefficient of about .0022 it will be desirable to cause it to change 3.3 ohms per degree Fahrenheit change in ambient temperature, thus the value of resistor R_a should be about 1500 ohms.

In the event the heater element should fail or the heater circuit should be otherwise broken the great increase in the resistance of this circuit will at one cause the relay to open. However, in order to positively retain the relay in its open condition I prefer to connect a resistor R_s of very high value across the relay terminals. Should the heater circuit open, the very small amount of current flowing through this safety resistor R_s will be sufficient to impress a high voltage on the cathode of tube V_1 , which will cause the condenser C_1 to remain charged and thus hold the relay open. The current in this safety resistor has no effect when the heater circuit is intact, since it amounts to less than $\frac{1}{2}$ milliampere. The condenser C_2 is connected across the relay circuit to prevent the relay from chattering.

While I have shown and described one embodiment of my invention, I wish it to be understood that I do not desire to be limited to the details thereof as various modifications may occur to a person skilled in the art.

Having now fully described my invention, what I claim as new and desire to secure by Letters Patent is:

1. An electric temperature control system comprising an electrical heater having a known temperature coefficient of resistance, an adjustable resistor, a bridge circuit including said heater and said resistor, an amplifier connected to said bridge circuit and controlled by changes in resistance in said bridge circuit, a relay controlled by said amplifier and adapted to energize said bridge circuit by selectively connecting said bridge circuit to a source of electrical power, timing means connected to said source of power and operable in response to de-energization of said bridge circuit by said relay to cause said relay to energize said bridge circuit after the elapse of a predetermined interval.

2. An electric temperature control system comprising a resistance element having a predetermined coefficient of resistance change with temperature, an adjustable resistor, a bridge circuit including said element and said resistor, relay means for selectively energizing said bridge circuit by connecting said bridge circuit to a source of electric power, an amplifier adapted to control said relay means in accordance with the relative resistances of said element and said resistor, when said bridge circuit is energized, and timing means connected to said source of power and operable to energize said bridge circuit in response to the elapse of a predetermined interval after said bridge is de-energized in response to operation of said relay.

3. In a controlled electrical heater system, a resistance heating element having a known variation of resistance with temperature, a bridge circuit including said element, a condenser, amplifying means connected to said bridge circuit for charging said condenser, resistor means for discharging said condenser at a predetermined rate, relay means for energizing said bridge circuit by connecting said bridge circuit to a source of electric power, and vacuum tube means for energizing said relay means in accordance with the charge across said condenser.

4. A controlled electric heater system comprising a resistance heater element having a known relation of resistance to temperature, an adjustable resistor, a second resistance element having a high resistance compared with said resistance heater element, a bridge circuit including said heater element, said resistor and said second element, an amplifier connected to said bridge circuit, relay means to energize said bridge circuit by connecting it to a source of electric power, said amplifier serving to control said relay in accordance with the resistance of said heater element, and timing means to control said relay in response to a predetermined change in the resistance of said bridge circuit, said timing means serving to energize said bridge circuit after a predetermined lapse of time following the de-energization of said circuit by said relay.

5. In a controlled electric heating system, a resistance heating element having a known coefficient of resistance with temperature, an adjustable resistor, a bridge circuit including said element and said resistor, a relay including a coil, said relay also including contacts which close when said coil is energized, said contacts being adapted to carry current from a source of electrical power to said bridge circuit, a vacuum tube including an anode connected to said coil, said vacuum tube also including a control grid and a cathode, said cathode and said coil being adapted to be connected to a source of electric power, a condenser and a second resistor connected between said grid and said cathode, a second vacuum tube including a second anode connected to said grid, said second vacuum tube also including a second grid and a second cathode, a third resistor connected from said second cathode to said first cathode, a fourth resistor connected from said second cathode to said coil, a fifth resistor connected from said second grid to said first cathode, a third vacuum tube including a third anode connected to said second grid, said third vacuum tube also including a third cathode and a third grid connected to said bridge circuit.

6. In a controlled electric heating system, a resistance heater element having a known temperature resistance coefficient, a second resistance element connected in series with said element, an adjustable resistor having a relatively high impedance compared with said first element and said second element, a third resistance element connected in series with said adjustable resistor and having an impedance in ratio to said adjustable resistor substantially equal to the impedance of said first element in ratio to said second element, said adjustable resistor, said first element, said second element and said third element comprising a bridge circuit in balance at a predetermined temperature of said first element, an amplifier having a pair of input terminals, one terminal of said pair being connected to the junction of said first element and said second element, the other terminal of said pair being

connected to the junction of said adjustable resistor and said third element, a power circuit having a second pair of terminals one of said second pair being connected to the junction of said first element and said third element, the other of said second pair being connected to the junction of said second element and said adjustable resistor, a relay having a coil and a switch contact, said contact being adapted to energize said power circuit from a source of electric power in response to energization of said coil, vacuum tube means to selectively energize said coil, said vacuum tube means being in part controlled by said amplifier in response to energization of said power circuit, and timing means in part controlling said vacuum tube means in response to de-energization of said bridge circuit upon opening said switch contact.

7. In an electric temperature control system, a circuit having terminals A and B whereby it may be connected with an alternating current power line, a resistance heater in said circuit, a relay including a switch arranged to control the flow of current through said heater, and an amplifier in said circuit including a vacuum tube the plate circuit of which is connected with terminal B through the winding of said relay, a second vacuum tube the plate circuit of which is connected with terminal A and includes a resistor and a condenser in parallel with said resistor, the plate circuit of said second tube and said condenser being connected with the grid of the first mentioned tube, a voltage divider connected with both terminals A and B, and the cathode of said second tube being connected with said divider between the ends thereof, a third vacuum tube the plate circuit of which is connected with terminal A and includes a resistor, means connected with said terminal B to impress a negative voltage on the cathode of said third tube and a smaller negative voltage on the grid thereof when terminal B is negative, said grid voltage being responsive to variations in the resistance of said heater, the grid of said second tube being connected with the plate circuit of said third tube in advance of the resistor in said plate circuit, and means including a high resistance in parallel with said switch for impressing a high positive voltage on the cathode of said third vacuum tube so as to cause said condenser to remain charged and hold the relay open at all times in the event the resistance heater breaks.

8. An electric temperature control system comprising an electrical heater having a known temperature coefficient of resistance, an adjustable resistor, a bridge circuit including said heater and said resistor, an amplifier connected to said bridge circuit and controlled by changes in resistance in said bridge circuit, a relay controlled by said amplifier and adapted to energize said bridge circuit by selectively connecting said bridge circuit to a source of electrical power, timing means connected to said source of power and operable in response to de-energization of said bridge circuit for a predetermined period of time for causing said relay to energize said bridge circuit, and means for rendering said timing means inoperative in response to a break in the electric heater circuit.

9. In a temperature control system for use with an electrically heated blanket, the combination including an electrical heater disposed within said blanket, said heater having a known temperature coefficient of resistance so that the resistance of the heater changes in response to

changes in temperature in the blanket, a second resistance located outside of said blanket and having a known temperature coefficient of resistance so that the resistance of said second resistance varies in response to ambient temperatures, relay operated switching means for open-circuiting the heater circuit, means responsive to the resultant of the voltage drop across the heater and the second resistance for open-circuiting the heater when the temperature within the blanket reaches a predetermined value, which predetermined value is influenced by changes in the ambient temperature, and timing means operable after the elapse of a predetermined interval to close said switching means to energize said heater.

10. In a temperature control system for use with an electrically heated blanket, the combination including an electrical heater disposed within said blanket, said heater having a known temperature coefficient of resistance so that the resistance of the heater changes in response to changes in temperature in the blanket, a second resistance located outside of said blanket and having a known temperature coefficient of resistance so that the resistance of said second resistance varies in response to ambient temperatures, relay operated switching means for open-circuiting the heater circuit, means responsive to the resultant of the voltage drop across the heater and the second resistance for open-circuiting the heater when the temperature within the blanket reaches a predetermined value, which predetermined value is influenced by changes in the ambient temperature, timing means operable after the elapse of a predetermined interval to close said switching means to energize said heater, and means responsive to abnormal circuit conditions for making said timing means inoperative to prevent accidents.

11. A control for an electric heating device having a heating winding adapted to change its resistance with change in its temperature, relay means having contacts in circuit with said heating winding, means for intermittently momentarily closing said contacts for energizing said heating winding and means including an electron tube circuit responsive to the resistance of said heating winding for energizing said relay to hold said contacts closed until said heating winding reaches a predetermined temperature.

12. A control for an electric blanket having a heating winding with a high temperature coefficient of resistance comprising, in combination therewith, means for establishing a change of potential in response to a change in resistance of said winding, means for comparing said potential with a reference potential and thereby deriving a control potential, an electron tube circuit, means applying said control potential to the input of said circuit and thereby producing a change in the output current thereof, relay means having contacts in circuit with said heating winding and adapted to be operated by said output current to disconnect said heating winding from a supply source and means operable at the beginning of each heating interval to close said contacts.

13. A control for an electric blanket having a heating winding with a high temperature coefficient of resistance comprising, in combination therewith, a resistor in series with said winding whereby the potential drop across said resistor varies in accordance with current flow through said winding, means comparing said potential

drop with a reference potential and thereby deriving a control potential, an electron tube circuit, means applying said control potential to the input of said circuit and thereby producing a change in the output current thereof, relay means having contacts in circuit with said heating winding and adapted to be operated by said output current to disconnect said heating winding from a supply source and means operable at the beginning of each heating interval to close said contacts.

14. A control for an electric blanket having a heating winding with a high temperature coefficient of resistance comprising, in combination therewith, a resistor in series with said winding whereby the potential drop across said resistor varies in accordance with current flow through said winding, a resistance bridge network having said winding in one leg and said series resistor in an adjacent leg, means applying a potential to said network, an electron tube circuit, means applying the unbalance bridge potential to the input of said circuit and thereby producing a change in the output current thereof, relay means having contacts in circuit with said heating winding and adapted to be operated by said output current to disconnect said heating winding from a supply source and means operable at the beginning of each heating interval to close said contacts.

15. A control for an electric blanket having a heating winding with a high temperature coefficient of resistance comprising, in combination therewith, a resistor in series with said winding whereby the potential drop across said resistor varies in accordance with current flow through said winding, a resistance bridge network having said winding in one leg and said series resistor in an adjacent leg, means applying a potential to said network, an electron tube circuit, having

40

an output tube normally biased to produce an output current, relay means having contacts in circuit with said heating winding and an operating coil connected to said output tube and adapted to be operated by said output current to close said contacts thereby connecting said heating winding to a supply source, means applying the unbalance bridge potential to the input of said electron tube circuit, said circuit being adapted to cut off said normal output current in said output tube and thereby open said relay contacts in response to a predetermined increase in said heating winding resistance and means operable at the beginning of each heating interval to close 15 said contacts.
